Primary Examiner — Susan Bennett Hattan*Assistant Examiner* — Marie D. Fast Horse(74) *Attorney, Agent, or Firm* — Wagenknecht IP Law Group PC(57) **CLAIM**

What is claimed is an ornamental design for a computer keypad, as shown and described.

DESCRIPTION

FIG. 1 is a top, back, left isometric view of a computer keypad showing our new design;

FIG. 2 is a top plan view thereof;

FIG. 3 is a bottom plan view thereof;

FIG. 4 is back elevational view thereof;

FIG. 5 is a front elevational view thereof;

FIG. 6 is right side elevational view thereof; and,

FIG. 7 is a left side elevational view thereof.

wherein the broken lines in the drawing depict portions of the computer keypad that form no part of the claimed design.

1 Claim, 4 Drawing Sheets(56)
